UNITED STATES PATENT OFFICE.

ADOLPH WIEN, OF PRAGUE, AUSTRIA-HUNGARY.

BASKET-GRAVE FOR DRYING PURPOSES.

No. 927,699.

Specification of Letters Patent.

Patented July 13, 1909.

Application filed March 20, 1907. Serial No. 363,365.

To all whom it may concern:

Be it known that I, ADOLPH WIEN, subject of Austria-Hungary, residing at Prague, Kingdom of Bohemia, Empire of Austria-Hungary, have invented new and useful Improvements in Basket-Grates for Drying Purposes, of which the following is a specification.

This invention relates to improvements in basket grates for drying or heating purposes.

The object of the invention is to produce a grate which will have increased efficiency and which may be used for drying damp rooms and particularly the corners thereof.

These and further objects will appear from the following specification and accompanying drawings, considered together or separately:

20 In the drawings, Figure 1 is a cross sectional view taken on the line $y-y$ of Fig. 2 of a basket grate embodying my invention; and Fig. 2 is a sectional plan view of the same taken on the line $x-x$ of Fig. 1.

25 In both views like parts are designated by the same reference characters.

In carrying out my invention I provide a basket grate a of the customary type, the said basket grate having an imperforated 30 cover b , the said cover tapering upward. Upon the top of the cover is a flat box d . In the center of this box is a pipe c which projects slightly above the bottom of the box and passes through the grate. Fresh air 35 is introduced through this pipe. In the top of the box d , a plurality of apertures e are provided, arranged preferably on both sides of the mouth of the pipe c . These apertures are provided with pipe sockets f , which are 40 adapted to engage with pipes h . Suitable covers l are provided for the purpose of closing these apertures when desired. The apertures e are situated above corresponding apertures g formed in the bottom of the box 45 d . The gases of combustion and the hot air thus will flow through the apertures g into the box d and from thence into the pipes h .

In accordance with the structure described there results, by using the box d , several currents of hot air which may be utilized according to requirements. As an example, at the beginning of the drying operation, the current of hot air only may be allowed to escape through the pipe c' , such pipe c' being in line with the pipe c , and the mouths of the pipe sockets f may be closed by their

covers l . When the drying has proceeded further, one or more of the lateral pipe sockets f are opened according to requirements by taking off the covers; by placing the pipes h on the sockets f , these pipes may be led to the corners of the room, which, of course, dry more slowly than does the center; or the pipes may be led into adjacent rooms, which may in this manner be dried 65 without any separate drying apparatus being necessary therein.

For the purpose of further utilizing the fuel consumed in the basket grate, it may be provided with lateral contractions or grooves 70 z , in which will lie pipes or tubes k . Through these pipes fresh air from the outside may be conveyed in the same manner in which it is conveyed to the pipe c . The air heated in the pipes k may be utilized for further 75 drying the room.

In accordance with the provisions of the patent statutes, I have described the principle of my invention, together with the apparatus which I now consider to represent 80 the best embodiment thereof, but I desire to have it understood that the apparatus shown is merely illustrative and that the invention can be carried out in other ways.

Having now described my invention, what 85 I claim as new and desire to secure by Letters Patent, is:

1. A basket grate having a box on the top thereof apertures connecting the grate and the box, a central pipe passing through the 90 grate and entering the box, and apertures in the top of the box.

2. A basket grate having a box at the top, a central pipe passing through the grate and communicating with the box, an aperture 95 in the top of the box above the end of this pipe, other apertures at the top of the box, apertures in the bottom of the box, communicating with the grate, and in line with the apertures in the top, the top apertures 100 having pipe sockets, with means for closing the same.

3. A basket grate having lateral contractions or grooves in the side, in combination with air pipes lying within the grooves. 105

In testimony whereof I have signed my name to this specification in the presence of two subscribing witnesses.

ADOLPH WIEN.
